UNITED STATES PATENT OFFICE.

LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY.

WATER-COOLED SKEWBACK FOR FURNACES.

1,267,085.

Specification of Letters Patent.

Patented May 21, 1918.

Application filed July 17, 1916. Serial No. 109,651.

To all whom it may concern:

Be it known that I, LUTHER L. KNOX, a citizen of the United States, residing at Bellevue, in the county of Allegheny and State of Pennsylvania, have invented a new and useful Improvement in Water-Cooled Skewbacks for Furnaces, of which the following is a full, clear, and exact description, reference being had to the accompanying drawings, forming part of this specification, in which—

Figures 1 and 2 are detail sectional views of a portion of a furnace structure and showing two different forms of my invention.

Fig. 3 is a front view, partly broken away, of the skew-back.

My invention has relation to water cooled skew-backs for water cooled furnaces and is designed to provide a skew-back in which the metallic frame member may be readily formed from a single piece of sheet metal, and which will provide means for retaining the brick or refractory portion of the skew-back in place.

Referring first to that form of my invention shown in Fig. 1, the numeral 2 designates a portion of a furnace wall, 3 the supporting frame and 4 the roof arch. 5 designates the metallic member of the skew-back for the roof arch 4. This member consists of an initially flat plate or sheet of metal of the requisite length of the particular structure in hand. One edge portion of this structure is bent around upon itself to form an approximately rectangular longitudinally extending water circulating cavity 6, the free edge of this bent portion being welded to the body of the plate at the point 40 where the bend starts, as indicated at 7. The upper edge portion of the plate is preferably flanged backwardly, as shown at 8, in order to form a reinforce and to give, with the lower bent portion, a channel-form 45 to the plate. Nipples 9 can be welded or otherwise secured to the water cooled portions in order to provide for the connection of water circulating pipes 10.

The construction shown in Fig. 2 is similar to that shown in Fig. 1 and the same reference characters have been applied to corresponding parts with the affix "a" added thereto. Instead, however, of forming the water containing box or chamber in rec-

tangular form, the sheet or plate 5a is so bent upon itself as to form a triangular water containing box or chamber 6a, the triangle having its base at the bottom of the wall 7a being at the apex.

In both forms of my invention the bent portion of the plate forms a support for the refractory portion 11 or 11a of the skew-back and which forms the actual abutment for the edge of the roof arch.

The ends of the water circulating box or chamber may be closed in any suitable manner as by welding end plates 12 thereto, these plates being preferably inset as shown in Fig. 3.

My invention provides a form of skew-back which can be readily constructed from sheet metal at a relatively low cost and which is greatly superior to cast metal structures, being less liable to crack or break in service, due to warping, and contraction and expansion thrusts. Obviously the particular shape of the metallic member and of the water cooled portion thereof may be changed without departing from the spirit and scope of my invention.

I claim:

1. A water-cooled skew-back member comprising a sheet metal member, having a portion thereof bent upon itself to form a hollow longitudinal extending water circulating chamber, the free edge of the bent portion being welded to the body portion of the sheet at the junction of the body portion of the sheet and the bent portion, said sheet extending beyond the water circulating chamber to form a support for the refractory portion of the skew-back, substantially as described.

2. A skew back member formed of sheet metal having a water circulating chamber and an upwardly extending portion which forms a support for the refractory portion of the skew back above the water circulating chamber, said water circulating chamber being formed by bending the sheet laterally and downwardly, then laterally and then upwardly, the free edge of the upwardly bent portion being secured to the body of the sheet, the upwardly bent portion lying in approximately the same plane as the upwardly extending portion; substantially as described.

3. A water-cooled skew-back member for

furnaces, comprising a sheet metal member having a portion thereof bent upon itself to form a hollow longitudinally extending water circulating chamber, the free edge of 5 the bent portion being secured to the body portion of the sheet, and said bent portion extending into and forming a support for the refractory portion of the skew-back, said plate having its upper edge portion bent to

form a reinforcement; substantially as described.

In testimony whereof, I have hereunto set my hand.

LUTHER L. KNOX.
